UNITED STATES PATENT OFFICE.

RICHARD T. DAVIS, OF CHICAGO, ILLINOIS.

DESIGN FOR A GRILLE FOR MUSICAL INSTRUMENT.

Application filed October 7, 1926. Serial No. 19,271. Term of patent 14 years.

To all whom it may concern:

Be it known that I, RICHARD T. DAVIS, a citizen of the United States, residing at Chicago, county of Cook, and State of Illinois, have invented a new, original, and ornamental Design for a Grille for Musical Instrument, of which the following is a specification, reference being had to the accompanying drawing, forming a part hereof, in which the figure is a front elevation of the grille.

I claim:

The ornamental design for a grille for musical instrument as shown.

RICHARD T. DAVIS.
